UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed August 4, 1926. Serial No. 127,007.

My invention relates to railway signaling apparatus and particularly to apparatus of the type involving track circuits.

I will describe three forms of apparatus embodying my invention, and will then point out the novel features thereof in claims.

In the accompanying drawing, Fig. 1 is a diagrammatic view showing one form of apparatus embodying my invention. Fig. 2 is a diagrammatic view showing a modified form of apparatus embodying my invention and suitable for use in connection with two track circuits the track relays of which are located adjacent the point of junction of the two circuits. Fig. 3 is a diagrammatic view showing a further modification of my invention suitable for use in connection with two parallel tracks.

Similar reference characters refer to similar parts in each of the views.

Referring first to Fig. 1, the reference characters 1 and 1^a designate the rails of a railway track, which rails are divided by insulated joints 2 to form a section E—F. This section is provided with a track circuit comprising a transformer T^E having its secondary connected across the rails through a limiting reactance 29, and a track relay R having two windings 6 and 7, the former of which is connected across the rails of the section. The primary of the transformer T is constantly energized from a source of alternating current not shown in the drawing. The second winding 7 of track relay R is also supplied with alternating current from the secondary of a transformer L, the primary of which is constantly energized from a suitable source of alternating current. Interposed between the secondary of transformer L and the winding 7 is a primary 5 of a transformer C, the secondary 4 of which is connected with the mid point of a reactance A and with an auxiliary conductor B. The reactance A is connected across the track rails 1 and 1^a of the section E—F, and the auxiliary conductor B is in contact with the track ballast. This conductor B is preferably located midway between the rails 1 and 1^a, and may, for example, be spiked to the usual ties which support these rails.

As is well understood in the railway signaling art, the ballast leakage resistance of a

track section, that is, the resistance from rail to rail through ties and ballast, varies through wide limits depending upon weather conditions. When the ballast is wet, this leakage resistance is comparatively low, but when the ballast is dry, the leakage resistance is comparatively high. It follows that with a substantially constant voltage across the primary of transformer T, the voltage across the rails adjacent relay R will be larger when the ballast resistance is high than when the ballast resistance is low. The voltage applied to winding 6 of relay R will therefore vary in accordance with the condition of the ballast, and in the absence of any preventive means the torque exerted by this relay will vary correspondingly.

Considering the transformer C, when the ballast resistance is high, the secondary 4 of this transformer is practically on open circuit, so that the current in the local winding 7 of relay R is reduced to a amount equal to the magnetizing current of the transformer C. When the resistance of the ballast is extremely low, the secondary 4 of transformer C is practically on short circuit, so that the full voltage of transformer L is applied to winding 7. The increased current in the local winding 7 of relay R will compensate for the reduced amount of current in the track winding 6 due to wet ballast conditions, and so it will be seen that practically a constant torque may be obtained in the track relay under all weather conditions. This permits high energization of the track circuit to take care of wet weather conditions without impairing the shunting sensitivity of the track circuit under dry weather conditions.

Referring now to Fig. 2, I have here shown two adjoining track sections E—F and F—G, which track sections are provided with track circuits so arranged that the two track relays R¹ and R² are located adjacent the point of junction F whereas the two track transformers T^F and T^G are located adjacent the outer ends of the track sections. The local windings 7 of the relays R¹ and R² are energized in multiple from the secondary 4 of transformer C. The terminals 105 of secondary 4 of transformer C are connected respectively with two conductors B¹ and B², the former of which is in contact

with the ballast in section E—F and the latter of which is in contact with the ballast of section F—G. The ratio of turns in the windings of transformer C are such as to obtain the same characteristics with the two relay windings 7 in circuit with this transformer as those obtained in Fig. 1 with but one relay winding connected with this transformer.

Referring now to Fig. 3, I have here shown two parallel railway tracks X and Y, each of which is divided into sections E—F and F—G. Section E—F of track X is provided with a track circuit which is the same as that shown in Fig. 1, and section F—G of track Y is provided with a similar track circuit. In this view the windings 7 of the two track relays R¹ and R² are energized in multiple from transformer L through primary winding 5 of transformer C, and the terminals of secondary 4 of the latter transformer are connected respectively with a reactance A¹ and a reactance A². Reactance A¹ is connected across the rails of section E—F of track X, whereas reactance A² is connected across the rails of section F—G of track Y. The characteristics and operation of the apparatus shown in Fig. 3 are the same as those of the apparatus shown in Figs. 1 and 2. That is, under dry weather conditions the secondary 4 of transformer C will be practically on open circuit, and under wet weather conditions this secondary will be practically on short circuit because of the low resistance of the ballast and ground between reactances A¹ and A². The primary 5 of transformer C will vary the amount of current supplied to the local windings 7 accordingly.

Referring now to all of the views, if the track relays are of the polyphase type requiring currents disposed in quadrature relation in their two windings for best operation, they will be protected against false operation due to any unbalance in the phantom leakage current, because any of phantom leakage current which flows through the track element of the relay will be nearly in phase with the current in the local winding 7 and will, therefore, produce practically no torque in the relay.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In a signal system involving a section of railway track, a source of track circuit voltage connected with the rails of said section and a track relay having a first winding receiving energy from said rails and a sec-

ond winding supplied with voltage, the combination with the aforementioned instrumentalities of an auxiliary conductor in contact with the track ballast, and a transformer having its primary included in circuit with said second winding and the terminals of its secondary connected with said conductor and the track rails.

2. In a signal system involving a section of railway track, a source of track circuit voltage connected with the rails of said section and a track relay having a first winding receiving energy from said rails and a second winding supplied with voltage, the combination with the afore-mentioned instrumentalities of an auxiliary conductor in contact with the track ballast, an impedance connected across the rails of said section, and a transformer having its primary included in circuit with said second winding and the terminals of its secondary connected with said conductor and an intermediate point in said impedance.

3. In a signal system involving a section of railway track, a source of track circuit voltage connected with the rails of said section, and a track relay having a first winding receiving energy from said rails and a second winding supplied with voltage, the combination with the afore-mentioned instrumentalities of a coil in series with said second winding, and means responsive to variations in the resistance of the track ballast for varying the effective reactance of said coil.

4. In a signal system involving a section of railway track, a source of track circuit voltage connected with the rails of said section, and a track relay having a first winding receiving energy from said rails and a second winding supplied with voltage, the combination with the afore-mentioned instrumentalities of an auxiliary conductor in contact with the track ballast, a coil in series with said second winding, and means responsive to variations in the resistance of the track ballast between said auxiliary conductor and the track rails for varying the effective reactance of said coil.

5. In combination with a section of railway track provided with a source of track circuit voltage and a track relay, an auxiliary conductor in contact with the track ballast, and a transformer having its primary included in circuit with a winding of said relay and its secondary terminals connected with said conductor and the track rails.

6. In combination with a section of railway track provided with a source of track circuit voltage and a track relay, an auxiliary conductor in contact with the track ballast, an impedance connected across the rails of said section, and a transformer having its primary included in circuit with a winding of said relay and the terminals of its sec-

ondary connected with said conductor and with an intermediate point in said impedance.

7. In combination with a section of railway track provided with a source of track circuit voltage and a track relay, an auxiliary conductor in contact with the track ballast, a coil in series with a winding of said

track relay, and means responsive to variations in the resistance of the track ballast between said auxiliary conductor and the track rails for varying the effective reactance of said coil. ¹⁰

In testimony whereof I affix my signature.

ROBERT M. GILSON.
